(57) **CLAIM**

The ornamental design for a mobile phone as shown and described.

DESCRIPTION

FIG. 1 is a front view of a mobile phone showing the new design;

FIG. 2 is a back view thereof;

FIG. 3 is a left side view thereof;

FIG. 4 is a right side view thereof;

FIG. 5 is a top view thereof;

FIG. 6 is a bottom view thereof;

FIG. 7 is a perspective view thereof;

FIG. 8 is a front view of the mobile phone of FIG. 1, showing a closed state;

FIG. 9 is a left side view thereof;

FIG. 10 is a top view thereof; and,

FIG. 11 is a perspective view thereof.

The broken lines shown in the drawings illustrate portions of the mobile phone that form no part of the claimed design. The dot-dash broken lines illustrate the boundary of the claimed design and form no part thereof.

1 Claim, 11 Drawing Sheets

Related U.S. Application Data

and having an international filing date of Dec. 31, 2021, now Pat. No. Des. 999,761.
